Primary Examiner — Brett Miller*(74) Attorney, Agent, or Firm* — Stinson LLP(57) **CLAIM**

The ornamental design for a plastic bag with textured strips, as shown and described.

DESCRIPTION

FIG. 1 is a front elevation of an embodiment of a plastic bag of the present invention, the plastic bag having four textured strips extending between the opening of the bag and the bottom of the bag, the rear elevation being a mirror image thereof;

FIG. 2 is a front elevation of another embodiment of the invention, the plastic bag having four textured strips extending between the opening of the bag and the bottom of the bag;

FIG. 3 is a front elevation of another embodiment of the invention, the plastic bag having four textured strips extending between the opening of the bag and the bottom of the bag; and,

FIG. 4 is a front elevation of another embodiment of the invention, the plastic bag having four textured strips extending between the opening of the bag and the bottom of the bag.

The shading in the figures depicts a texture contrast consonant with the visual appearance shown in these drawings. A front of each plastic bag is transparent, and vertical strips have stippling to show that the strips have a different texture, and therefore a texture contrast is depicted between the textured strips and the remainder of the bag.

The broken lines illustrate unclaimed environmental structure and form no part of the claimed design.
